US0D1013683S

(12) **United States Design Patent** (10) **Patent No.:** **US D1,013,683 S**
(45) **Date of Patent:** **** Feb. 6, 2024**

(54) **COMPUTING DEVICE**

(71) Applicant: **Microsoft Corporation**, Redmond, WA (US)

(72) Inventors: **Timothy G. Escolin**, Seattle, WA (US);
Jazmine Ama Hoyle, Seattle, WA (US);
Byungkwon Min, Kirkland, WA (US);
Ralf Groene, Kirkland, WA (US);
Panos Costa Panay, Redmond, WA (US);
Young Soo Kim, Bellevue, WA (US)

(73) Assignee: **Microsoft Corporation**, Redmond, WA (US)

(**) Term: **15 Years**

(21) Appl. No.: **29/808,693**

(22) Filed: **Sep. 22, 2021**

(51) LOC (14) Cl. **14-02**

(52) U.S. Cl.

USPC **D14/345**

CLAIM

The ornamental design for a computing device, as shown and described.

DESCRIPTION

FIG. 1 is a front perspective view of a computing device showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the computing device of FIGS. 1-7 shown in an alternative configuration;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a front perspective view of the computing device of FIGS. 1-7 shown in an alternative configuration;

FIG. 16 is a front view thereof;

FIG. 17 is a rear view thereof;

FIG. 18 is a right-side view thereof;

FIG. 19 is a left side view thereof;

FIG. 20 is a top view thereof;

FIG. 21 is a bottom view thereof;

FIG. 22 is a front perspective view of the computing device of FIGS. 1-7 shown in an alternative configuration;

FIG. 23 is a front view thereof;

FIG. 24 is a rear view thereof;

FIG. 25 is a right-side view thereof;

FIG. 26 is a left side view thereof;

(Continued)

FIG. 27 is a top view thereof; and,
FIG. 28 is a bottom view thereof.

The broken lines represent portions of the computing device and form no part of the claimed design.
